R. T. HORTON

FIRING DOOR FOR BOILERS AND FURNACES

Filed June 7, 1924

UNITED STATES PATENT OFFICE.

ROBERT T. HORTON, OF GREENWOOD, INDIANA.

FIRING DOOR FOR BOILERS AND FURNACES.

Application filed June 7, 1924. Serial No. 718,469.

To all whom it may concern:

Be it known that I, ROBERT T. HORTON, a citizen of the United States, and a resident of Greenwood, county of Johnson, and State 5 of Indiana, have invented a certain new and useful Firing Door for Boilers and Furnaces; and I do hereby declare that the following is a full, clear, and exact description thereof, reference being had to the accompanying drawings, in which like numerals refer to like parts.

This invention pertains to a foot actuated door for the fire box of a boiler, furnace, or the like.

15 The object of the invention is to so arrange a fire box door and actuating mechanism as to permit the same to readily be swung to open position by the fireman when he places his foot on a suitable pedal where- 20 by his hands will be free to throw in the fuel. Upon completing the firing operation, by simply removing his foot, the door will drop by gravity to closed position. There are 25 two principal advantages to the invention, one lying in the saving of fuel by reason of the fact that the door will remain closed excepting just at the time the fuel is thrown into the fire box, instead of remaining open during the entire time the boiler or furnace 30 is being fired. Another advantage lies in the ease with which the fireman can handle the fuel while controlling the position of the door with his foot.

One feature of the invention resides in 35 the arrangement and mounting of the door on the wall of the fire box so as to be provided with a protective hood which will not only cover the actuating lever but will assist in the pivotal support of the door and relieve 40 the strain on the pivotal stud and its connection with the wall.

Another feature of the invention resides 45 in the positioning of the foot pedal or actuating pin with the associated actuating mechanism below the floor, and its position with respect to the door such as to permit its more convenient operation by the fireman when shoveling the fuel therein.

Other features of the invention, as will be 50 hereinafter more fully set forth and described, pertain to the leverage arrangement of the actuating mechanism, such as will insure a more practical and commercial structure.

55 The full nature of the invention will be

understood from the accompanying drawings and the following description and claims:

Fig. 1 is a front elevation of the fire box showing the door in closed position. Fig. 60 2 is the same as Fig. 1 showing the door in open position. Fig. 3 is a section taken on the line 3—3 of Fig. 1.

In the drawing there is shown a wall 10 of a fire box or furnace in which there is the 65 usual opening 11 through which fuel is passed or the fire stoked. The opening 11 is closed by a sliding door 12 which is pivotally supported on the wall by a stud 13. The door 12 is adapted to lie flush against 70 the front surface of the wall and be capable of sliding up and down with respect thereto, so that when it is in lowered position as shown in Fig. 1 it will rest against the fixed bumper 14 and close the opening 11, and 75 when swung to open position about the stud 13, will uncover the opening 11 and permit access to the interior of the fire box. The arcuate guide member 15 is secured to the front face of the wall and is provided with 80 a flange portion adapted to embrace the corresponding arcuate head of the door, the stud 13 being located at the center of curvature thereof. The flange of said member acts to hold the free edge of the door against 85 the surface of the wall so that the door will make a substantially air-tight closure. Said door is provided with the usual damper 16 for permitting the access of air to the fire box at such times as may be desired without opening the door.

The door is provided on the other side of the stud 13 with an arm portion 17 formed integral therewith, which is of sufficient weight to substantially counterbalance the 95 weight of the door proper, the stud 13 acting as a fulcrum. However the weight of the arm 17 is slightly less than that of the door proper, so that the door may fall by gravity to closed position. The arm 17 is connected 100 with the actuating mechanism by a downwardly extending rod 18 which is pivoted to said arm at 19, the lower end of said rod extending through the floor 20.

Said arm 17 and the upper end of the rod 105 18 are covered and protected by the hood 21 which is rigidly secured to the wall of the fire box by the bolts 22. The stud 13 passes through said hood so that the outer end of said stud is supported thereon. By means 110

of this arrangement a relatively large area of the wall is adapted to support the door and the stud upon which it is fulcrumed.

On the under side of the floor 20 immediately below the door, there is a downwardly extending bracket 23 to which the cross lever 24 is pivoted at 25, said lever having its free end pivotally connected with the rod 18. Extending directly away from the wall 10 there is a beam 26 which is pivoted at 27 to a suitable bracket 28 suspended from beneath the floor. The free end of said beam is outwardly connected with the cross lever 24 intermediate the ends thereof. At a suitable position in the floor 20 and spaced the desired distance from the wall 10 there is a foot pedal or plunger 29 which extends through the floor and protrudes a short distance above the surface thereof, the lower ends of said pedal being bifurcated so as to straddle the beam 26 and ride thereon.

It will be observed from the foregoing that upon it being desired to fire the boiler the fireman having a shovel of fuel ready to throw into the fire, will place his foot upon the pedal 29 and push it down flush with the surface of the floor. This will throw the free end of the beam 26 downwardly, which in turn will force the free end of the lever 24 down, which, being connected with the rod 28 will pull said rod and the arm 17 to which it is connected downwardly. This movement will cause the door 12 to be raised about the stud 13 as a fulcrum, the movement being such as to cause the door proper to clear the opening 11. The fuel may then be thrown through said opening. Thereafter, upon the fireman removing his foot from the pedal the door will immediately drop by gravity against the bumper 14 which will hold it in closed position.

For holding the door in open position, it may be provided with an eye 30 for receiving a hook 31 secured to the wall 10. The rod 18 may also be provided with a turn-buckle 32 for adjusting its length, and the lever 24 may have an enlarged counter-weight portion 33, whereby the mechanism may be properly adjusted and balanced to assist in its operation.

The invention claimed is:

1. The combination with the wall of a fire box or the like having an opening therein, a door associated therewith, and a floor, of means for controlling the position of said door comprising a rod connected therewith extending through the floor, a lever having one end connected with said rod and the other end pivotally connected with the under side of said floor, said lever extending thereunder substantially parallel with said wall, a beam having one end pivotally connected with the under side of said floor and the other end connected with said lever, said beam extending away from said wall at substantially right angles thereto, and a pedal member mounted on said beam and projecting upwardly through said floor in position to be accessible for the operation thereof.

2. The combination with the wall of a fire box or the like having an opening therein, a door associated therewith, and a floor, of means for controlling the position of said door comprising a rod connected therewith extending through the floor, a lever having one end connected with said rod and the other end pivotally connected with the under side of said floor, said lever extending thereunder substantially parallel with said wall, a beam having one end pivotally connected with the under side of said floor and the other end connected with said lever, said beam extending away from said wall at substantially right angles thereto, and a pedal member having a bifurcated end adapted to straddle and rest upon said beam, the other end projecting upwardly through said floor in position to be accessible for the operation thereof.

2. The combination with the wall of a fire box or the like having an opening therein, a door associated therewith, and a floor, of means for controlling the position of said door comprising a rod connected therewith extending through the floor, a lever having one end connected with said rod and the other end pivotally connected with the under side of said floor, said lever extending thereunder substantially parallel with said wall, a beam having one end pivotally connected with the under side of said floor and the other end connected with said lever, said beam extending away from said wall at substantially right angles thereto, and a pedal member having a bifurcated end adapted to straddle and rest upon said beam, the other end projecting upwardly through said floor in position to be accessible for the operation thereof.

3. The combination with the wall of a fire box for boilers or the like having an opening therein, and a door for closing said opening, of a stud for pivotally supporting said door having one end secured in said wall, and actuating means connected with said door for causing it to swing to open or closed position upon said stud, and a hood rigidly secured on said wall so as to cover the connection between said door and actuating means and receive the other end of said stud for partially sustaining the weight of said door.

4. The combination with the wall of the fire box or the like having an opening therein, a door associated therewith, and a floor, of means for controlling the position of said door comprising a rod connected therewith extending through the floor, a lever having one end connected with said rod and the other end pivotally connected with the under side of said floor, said lever extending thereunder substantially parallel with said wall, a beam having one end pivotally connected with the under side of said floor and the other end connected with said lever, said beam extending away from said wall at substantially right angles thereto, a pedal member having a bifurcated end adapted to straddle and rest upon said beam, the other end projecting through said floor in position to be accessible for the operation thereof, and a hood secured to said wall for enclosing the connection between said rod and door and supporting the other end of said stud for partially sustaining the weight of said door, substantially as shown and described.

In witness whereof, I have hereunto affixed my signature.

ROBERT T. HORTON.
